UNITED STATES PATENT OFFICE.

PAUL GINELEWITZ, OF NEW YORK, N. Y.

DOUBLE-LOCKED SECRET CHAMBER.

Application filed August 21, 1922. Serial No. 583,202.

To all whom it may concern:

Be it known that I, PAUL GINELEWITZ, a citizen of the United States, residing at New York, in the county of New York and State of New York, have invented certain new and useful Improvements in Double-Locked Secret Chambers, of which the following is a specification.

This invention relates to chambers of compartments so arranged as to provide protection for valuables, as documents, jewelry, etc.

The main object of the invention is to provide a household article as a clock, with a stand having a concealed space, not readily observable and which would ordinarily be considered as containing part of the clock.

A further purpose is to provide means of access to the chamber from the rear, the closure being positively held by interior devices releasable only upon the withdrawal of an ordinary drawer arranged in the lower part of the stand.

Another aim is in the provision of an ornamental and useful stand for the clock, the same camouflaging its real purpose, that is the secret compartment.

These objects are attained by the novel construction and combination of parts hereinafter described and shown in the accompanying drawing, forming a material part of this disclosure, and in which:—

Figure 1 is a front elevational view of a structure embodying the invention.

Figure 2 is a transverse sectional view taken on line 2—2 of Figure 1.

Figure 3 is a partial side elevational, partial sectional view of the same, showing the drawer and chamber as in a locked position.

Figure 4 is a similar but fragmentary view, showing the parts in an unlocked position.

In the drawing, the numeral 10 designates a conventional clock face, set on a casing 11, the same being secured in a stand 12 having a gable roof 13, the sides of the stand rising from a platform 14.

Below the platform is a frame 15 resting upon feet 16, the same being suited to rest upon a shelf, or the like as is usually provided for a clock.

The rear portion of the stand 11 is extended to the rear beyond the clock works 10' and is provided with a pair of doors 17 engaged by hinges 18 at their outer edges,

one of the doors overlapping the other as at 17'.

Said doors abut against a cleat 19 fixed at the lower edge to the platform 14 and provided with openings to permit passage of hooks 20 fixed on the inner sides of the door 17 these hooks having beveled front surfaces 20'.

In the upper part of the frame 15 is slidably mounted a drawer 21 having a lock 22, engageable with a keeper 23 fixed to the lower side of the platform and carried at the rear of the drawer bottom, on its underside, is an open loop 24.

A lever 25 is pivoted between the sides of the frame 15, below the drawer, on a rod 26, its front end being bent upward and backward, forming a hook 27 adapted to be engaged by the loop 24 when the drawer is unlocked and drawn fully forward, as shown best in Figure 4.

The lever is held upward at its rear end by a bent flat spring 28 and is pivotally attached to the lower end of a detent 29 extending vertically upward, beyond the rear wall of the drawer, through the platform to normally engage the hooks 20, thus holding the doors 17 securely locked.

In operation, after releasing the drawer 21, it is pulled outwardly, causing the loop 24 to engage the hook 27, thus tilting the lever, opposing the spring and withdrawing the detent from the hook fixed on the doors, permitting them to be opened and gain access to the compartment behind the clock works.

When the drawer is in closed position the doors are held positively from opening but should they be open before the drawer is entered they can be closed, the bevelled faces of the hooks 20 pressing the detent 29 downwardly against the pressure of the spring 28, permitting the hooks to pass over the edge of the detent and become engaged by it.

Having thus described my invention, what I claim as new and desire to secure by Letters Patent, is:—

A chambered casing comprising a stand, one or more doors hinged at the back of the casing, hooks on said doors extending into the chamber in said stand, a frame below said stand, a drawer operable in said frame, a lock for the drawer, an open loop fixed on the bottom of said drawer, near the rear thereof, a lever pivoted in said frame, a

cam hook on the front end of said lever engageable by said loop upon moving the drawer outwardly, a detent pivoted to the lever at its rear end, said detent extending 5 past the inner end of said drawer and normally engaging the hooks carried by said doors, preventing opening thereof, and a

spring bearing against said lever to normally hold said detent in engagement with said hooks, the action of said loop on said cam hook moving the detent out of engagement. 10

In witness whereof I have affixed my signature.

PAUL GINELEWITZ
